UNITED STATES PATENT OFFICE.

ELMER J. TETREAULT, OF NEW BEDFORD, MASSACHUSETTS.

LENO JUMPER ATTACHMENT.

Application filed May 25, 1928. Serial No. 280,525.

The invention relates to attachments for looms, constructed to enable the weaving of cloth known as leno, for without such attachment or equipment, leno weaving is impossible.

It is the object of my invention to provide a rather simple and inexpensive, yet an efficient, smoothly operating attachment, by the use of which almost any desired number of harness actuators may be operated.

A further object is to provide a construction which is applicable to any make of loom and will operate to equal advantage thereon.

With the foregoing in view, the invention resides in the novel subject matter herein-after described and claimed, description being accomplished by reference to the accompanying drawings.

Fig. 1 is a side elevation showing the application of the invention.

Fig. 2 is a somewhat enlarged side elevation showing the operating levers for the harness actuators, swung to a different position.

Fig. 3 is an enlarged side elevation similar to Fig. 2 but showing a different position of parts.

Fig. 4 is an end elevation of a portion of a loom equipped with the invention, parts being broken away and in section.

Fig. 5 is a view similar to Fig. 4 but showing a somewhat different relation of parts.

The general form of construction herein disclosed, has proven in actual service, to be efficient and desirable from all standpoints. Hence, it may be considered as preferred, with the understanding that within the scope of the invention as claimed, variations may be made.

The numerals 6 denote two, spaced, vertical bars whose lower ends may be secured by bolts 7 against the inner side of a dobby head frame 8, or against the outer side thereof, the first arrangement being shown in most views while Fig. 5 discloses the latter. In some looms, it is more advantageous to secure the bars 6 to the inner side of the frame 8, while in others it is practically essential that they be secured to the outer side.

The bars 6 are provided with upper and lower bearings 9—10, in which upper and lower horizontal shafts 11—12 are mounted.

Two parallel vertical levers 13 are fulcrumed between their ends upon the upper shaft 11 and may be disposed either at the inner ends of the bearings 9 or at the outer ends thereof, as will be seen by comparing

Figs. 4 and 5. In either instance appropriate collars 14 may be secured on the shaft to hold the latter against endwise movement and to hold the levers 13 against sliding along said shaft.

The lower ends of the levers 13 are provided with straight track portions 15 contacting with rollers 16 carried by two arms 17 which are secured to the shaft 12 by set screws 65 or the like, said arms being disposed either at the inner ends of the bearings 10 as in Fig. 4 or at the outer ends thereof as seen in Fig. 5, according to the manner in which the bars 6 and the levers 13 must be positioned.

A crank 18 is secured to one end of the shaft 12 and is connected by an appropriate pitman 19 formed of pivotally connected sections, with a wrist pin 20 on a fly-wheel 21, the latter being secured upon the top loom 75 shaft 22.

At the upper end of the levers 13, two brackets 23 are provided, each being of inverted L-shape in the preferred construction. The vertical portion 24 of these brackets are secured by bolts 25 to the upper ends of the levers 13, either against their outer sides as in Fig. 4 or against their inner sides as seen in Fig. 5, according to the distance which it is necessary to space said levers apart. When the levers 13 must be rather close together as in Fig. 4, the horizontal portions 26 of the brackets 23 project outwardly therefrom as seen in this view, but when said levers must be spaced apart a greater distance as in Fig. 5, 90 the bracket portions 26 project inwardly.

A horizontally elongated plate or bar 27 extends between the upper ends of the levers 13 and is disposed in substantially a vertical plane, the ends of this member which will hereinafter be termed a bar, being provided with feet 28 which may be secured by bolts 29 to the bracket portions 26 whether the latter project outwardly or inwardly from the levers 13. This bar 27 is provided with a plurality of small openings 30 through which to pass practically any desired number of harness actuators which are preferably in the form of wire rods 31. Collars 32 may be secured upon these rods in abutting contact with the outer side of the bar 27 and these collars may be locked to the rods after any desired adjustments have been made.

As the loom is operated, pitman 19 is reciprocated and through the medium of the crank 18, it oscillates the rock shaft 12. The arm-carried rollers 17 of this rock shaft co-act

with the track portions 15 of the levers 13, in smoothly oscillating the levers 13, without any jerky motion whatever. Oscillation of these levers causes inward and outward movement of the bar 27 to operate the harness actuators 31 in proper rhythm with other parts of the loom.

Not only is the attachment simple and inexpensive, but it may be readily applied to any make of loom and will be efficient and durable whether only a small number or a large number of the actuators 31 are to be operated.

The present attachment is part of necessary equipment to enable any loom to weave the so-called leno cloth. The attachment constitutes half of the action which works the so-called leno or doup for the cross yarn on leno weave cloth. To work simultaneously with the attachment but independently thereof, is what is known as the Philadelphia steel doup or heddle, which in weaving leno cloth operates or is known as being the top shed of the weave of leno doup yarn, while my attachment commonly called the jumper motion of this action, operates or controls the bottom shed or cross yarn. The attachment does not interfere with the forming of the shed, as it does not control the weaving of cloth or background of the pattern of weave in cloth, only acting when leno weave is desired. To weave leno cloth, there must be a certain number of plain weave harnesses and a certain number of leno or jumper weave harnesses. The attachment comes into play to weave the spots, flowers or the like in any pattern when the pattern chain brings into the play the so-called doup harnesses. The attachment controls the bottom shed of doup harnesses which is the slack or cross yarn, while the Philadelphia doup or heddle controls the top shed of same, when the loom is called into play to weave the leno effect in cloth.

I claim:

1. A loom attachment comprising a pair of spaced parallel oscillatory levers, means for mounting and means for oscillating said levers, and a bar connecting the upper ends of said levers, said bar having means for connecting a plurality of spaced harness actuators therewith.

2. A loom attachment comprising a pair of parallel oscillatory levers, means for mounting and means for oscillating said levers, a pair of brackets each having a vertical portion and a horizontal portion, means securing the vertical bracket portions to the upper ends of said levers, a bar extending between said brackets, and means securing said bar to

said horizontal bracket portions, said bar having means for connecting a plurality of spaced harness actuators therewith.

3. A loom attachment comprising a pair of parallel oscillatory levers, means for mounting said levers in either of two spaced relations, a bar extending between the upper ends of said levers, means for securing said bar to said levers when the latter are in either of said spaced relations, and means for oscillating said levers, said bar having means for connecting a plurality of spaced harness actuators therewith.

4. A loom attachment comprising a pair of parallel oscillatory levers, means for mounting said levers in either of two spaced relations, a bar extending between the upper ends of said levers, inverted L-shaped brackets whose vertical portions are applicable against either the outer or the inner sides of said levers to cause the horizontal portions of the brackets to project either outwardly or inwardly from the levers, means for securing said vertical bracket portions to said levers, means for securing the ends of said bar to said horizontal bracket portions, and means for oscillating said levers, said bar having means for connecting a plurality of spaced harness actuators therewith.

5. A loom attachment comprising a pair of parallel vertical levers, means connecting the upper ends of said levers and adapted for connection with a plurality of harness actuators, means mounting said levers between their ends, a rock shaft carried by said mounting means below the fulcrum axis of said levers, means for oscillating said rock shaft, and arms on said rock shaft having rollers contacting with the lower ends of said levers for oscillating the latter.

6. A loom attachment comprising two vertical bars and means for securing their lower ends to a dobby head, said bars being provided with upper and lower bearings, upper and lower horizontal shafts mounted in said bearings, a pair of vertical levers fulcrumed between their ends on said upper shaft, arms on the lower shaft having rollers in contact with the lower ends of said levers for oscillating the latter, a crank on said lower shaft and a pitman connected with said crank for oscillating said lower shaft, and a bar extending between and connected with the upper ends of said levers, said bar having means for connecting a plurality of harness actuators therewith.

In testimony whereof I have hereunto affixed my signature.

ELMER J. TETREAULT.
